UNITED STATES PATENT OFFICE.

GEORGE E. GIBBS, OF ATTLEBORO, MASSACHUSETTS.

DESIGN FOR A GARTER SLIDE.

Application filed May 12, 1925. Serial No. 13,418. Term of patent 3½ years.

To all whom it may concern:

Be it known that I, GEORGE E. GIBBS, a citizen of the United States of America, residing at Attleboro, county of Bristol, State of Massachusetts, have invented a new, original, and ornamental Design for a Garter Slide, of which the following is a specification, reference being had to the accompanying drawing, forming a part thereof.

The figure is a perspective view of a garter slide, illustrating my new design.

I claim:

The ornamental design for a garter slide, as shown.

GEORGE E. GIBBS.
